DESIGN FOR A TOY AIRPLANE

Roy E. Lyman, Kansas City, Mo.

Application July 21, 1944, Serial No. 114,493

Term of patent 3½ years

(Cl. D34—15)

To all whom it may concern:

Be it known that I, Roy E. Lyman, a citizen of the United States, residing at Kansas City, in the county of Jackson and State of Missouri, have invented a new, original, and ornamental Design for a Toy Airplane, of which the following is a specification, reference being had to the accompanying drawing, forming a part thereof,

Fig. 1 is a side elevational view of the toy airplane, showing my new design.

Fig. 2 is a top plan view thereof; and

Fig. 3 is a front elevational view thereof.

I claim:

The ornamental design for a toy airplane, as shown.

ROY E. LYMAN.
